(57) **CLAIM**

The ornamental design for a vehicle wheel front face, as shown and described.

DESCRIPTION

FIG. 1 is a perspective view of a front face of a wheel for a motor vehicle;

FIG. 2 is a front elevational view thereof; and,

FIG. 3 is a side elevational view thereof.

The broken lines are for illustrative purposes and form no part of the claimed design.

1 Claim, 3 Drawing Sheets

FIG. 1

FIG. 2

FIG. 3
